UNITED STATES PATENT OFFICE.

DANIEL E. STAIR, OF ELKHART, INDIANA.

SPLIT BUCKET.

Application filed August 17, 1922. Serial No. 582,481.

To all whom it may concern:

Be it known that I, DANIEL E. STAIR, a citizen of the United States, residing at Elkhart, in the county of Elkhart and State of Indiana, have invented certain new and useful Improvements in Split Buckets, of which the following is a specification.

This invention relates to a new and improved conveyor bucket, and more particularly to a two-part bucket adapted to be opened and closed by the action of gravity.

In conveyor buckets it is highly desirable that the opening and closing means comprise but few and simple elements, since the buckets undergo rough treatment and these elements are likely to become deranged or broken. It is further highly desirable that the operation be accomplished without the addition of bucket opening and closing ropes or cables which unduly complicate the conveying system.

In order to provide a system of maximum efficiency, the buckets must open and close rapidly and must dump cleanly and quickly.

It is an object of the present invention to provide a bucket of the character described which is formed in two parts adapted to be swung by gravity to the closed position when in the filling position and to be opened by gravity when unlatched while in discharging position. It is also an object to provide a gravity-operated latch for said bucket. It is a further object to provide a bucket which is simple in construction, composed of comparatively few parts and which is relatively inexpensive to manufacture.

Other and further objects will appear as the description proceeds.

Broadly, my bucket comprises two parts transversely divided upon a vertical plane and hinged together at the point above the center of gravity of the two parts. Supporting elements are provided located adjacent the hinge, and the weight of the bucket is so proportioned that when supported by these elements, the two parts close. Means are provided for automatically latching the bucket together when closed. A bail is provided connected to the two parts of the bucket preferably by flexible members so that the bail may swing out of the way when loading. The bail is attached at such points to the two parts that when suspended from the bail the two parts tend to swing open

to the discharging position. The latching means is preferably of a form adapted to be unlatched when brought in contact with any fixed object upon lowering the bucket.

I have illustrated a preferred embodiment of my invention in the accompanying drawings, in which—

Figure 1 is a side view of the bucket in the closed position, the open position being indicated in dotted lines;

Figure 2 shows a bucket as seen from above;

Figure 3 is an end view of the bucket; and

Figure 4 is a view similar to Figure 1 but showing a modified form of latch.

The bucket comprises the two parts 5 hinged together at the point 6. The supporting rollers 7 are fitted upon the bucket substantially in line with the hinge pivot. These rollers are held in place by cotter pins 75 8. The upper adjacent faces of the two bucket parts are cut away at 9 so as to permit the bucket to swing to the open position. The bottom 10 of each bucket part is sloped downwardly toward the center in order that 80 the bucket may quickly discharge its entire contents. The side walls of the bucket are also upon a slight inward slope. The catch 11 is located upon one half of the bucket and the latch 12 is carried by the bracket 13 85 upon the opposite half of the bucket. The latch 12 is provided with the actuating foot 14.

The bail comprises the rigid cross member 15 provided at either end with a rigid 90 frame 16. The ends of these frames 16 are connected by chains 17 to the straps 18, the latter being attached to cross straps 19 which are welded or otherwise secured to the interior of the bucket corners. The chains 17 95 are adjustably connected by eyes 17' to the straps 18. The rigid member 15 may be connected in any desired manner to a hanger or pulley or other element as desired.

The right hand bucket member 5 is provided with the lap strip 24 which overlaps the edge of the opposite member 5 when the bucket is closed and thus forms a strong and tight joint. The lap strip strengthens this part of the bucket and tends to prevent bulging or other deformation under load.

The guide angles 25 are secured to the lap strip 24 immediately below the rollers 7 and

as clearly shown in Figure 3, these angles are so proportioned as to positively guide the rollers to the supporting rails.

The form shown in Figure 4 is similar in all respects to that of the other figures, with the exception of the latch. The latch 12' of this form of the device is provided with the rearwardly extending arm 20 which is connected by the rod 21 to the operating lever 22, the latter being pivoted to the upper portion of the bucket in the bracket 23.

In the use of my bucket it is normally connected to the conveyor by means of the bail member 15, and suspended in that manner, is moved about by the conveyor. When thus suspended the pull of the chains 17 tends to separate the two parts of the bucket. This tendency, however, is overcome by the latch 12 and catch 11. When the form of bucket shown in Figures 1 to 3 is lowered so that the foot 14 of the catch engages the ground, a pile of discharged material, or any other substantially unyielding object, that end of the catch is moved upwardly and the catch is released. The bucket then swings open and its contents are quickly and cleanly discharged by gravity. The bucket, remaining in this open condition, is transported to the loading point or to some point where supporting members such as rails are provided adapted to engage the rollers 7. The bucket is lowered until these rollers 7 engage the supports and carry the weight of the bucket, the angles 25 serving to guide the rollers to the rails. Gravity then swings the two parts together and the latch 12 is cammed outwardly by the catch 11 and snaps into engagement with that catch.

It is to be noted that not only the bucket itself but the bucket latch are gravity-operated, no springs or similar devices being required.

The form of latch shown in Figure 4 is operated by so moving the conveyor that the arm 22 is brought into engagement with any substantially fixed object and is swung upwardly. This movement of the lever serves to release the two parts of the bucket, which are discharged. It will be observed that this form of latch may also be operated by bringing the arm 20 into engagement with any substantially unyielding object by lowering the bucket in contact with it in a manner similar to the other form of latch.

By reason of the fact that the bail is connected to the bucket by flexible members, the chains 17 permit the rigid bail members to swing substantially out of the way of the incoming material when the bucket is loaded. The eyes 17' may be adjusted so that the bucket hangs evenly. It is to be understood, of course, that the bucket is not a reclaiming bucket, but is adapted to be loaded from above when the two parts are in the closed position and latched together.

My improved bucket is extremely simple in design and rugged in construction. Its operation is accomplished entirely by gravity so that no additional bucket-operating ropes or similar elements are required.

It is to be understood that the forms shown are by way of example only and that the apparatus may be modified within the scope of the appended claims.

I claim:

1. A conveyor bucket comprising two parts hinged together, supporting elements located adjacent the hinge and adapted to engage support members to carry the weight of the bucket, the supporting elements and hinge being so related to each other and to the two bucket parts that when the weight of the bucket is carried by the supporting elements, the two parts are closed together by gravity, and a bail for said bucket connected to each part at such point that when suspended from the bail the hinged parts tend to swing open.

2. A conveyor bucket divided into two parts upon a transverse vertical plane, said parts being hingedly connected together at a point above the center of gravity of the two parts and inwardly, toward the dividing plane, from the center of gravity of each part whereby the parts are closed together by gravity when the bucket is suspended from points adjacent the hinges, supporting elements adjacent said hinges and a bail for said bucket connected to each part at points spaced outwardly from the hinged joint and above the centers of gravity of the parts whereby when suspended from the bail the parts tend to swing open.

3. A conveyor bucket comprising two parts hinged together, supporting elements located adjacent the hinge and adapted to engage support members to carry the weight of the bucket, the supporting elements and hinge being so related to each other and to the two bucket parts that when the weight of the bucket is carried by the supporting elements, the two parts are closed together by gravity, and means adapted to automatically lock the two parts together when closed.

4. A conveyor bucket comprising two parts hinged together, supporting elements located adjacent the hinge and adapted to engage support members to carry the weight of the bucket, the supporting elements and hinge being so related to each other and to the two bucket parts that when the weight of the bucket is carried by the supporting elements, the two parts are closed together by gravity, and gravity-actuated means adapted to automatically lock the two parts together when closed.

5. A conveyor bucket having projecting elements adapted to engage spaced supports to sustain the bucket and guide angles lo-

- cated upon the bucket adjacent the projecting elements to guide them to the support.
6. A conveyor bucket comprising two parts hinged together, supporting rollers located adjacent the hinge and adapted to engage support members to carry the weight of the bucket, and guide angles carried by one of the bucket parts adjacent the rollers and adapted to guide them to the support members.
7. A conveyor bucket comprising two parts hinged together, laterally extending members adjacent the hinge adapted to engage rails to support the bucket therefrom, the bucket parts closing together by gravity when supported from said members, and means connected to the bucket parts at points distant from the hinge whereby when the bucket is supported from said means the bucket parts tend to open by gravity.
- 15 8. A conveyor bucket comprising two parts hinged together, laterally extending
- members adjacent the hinge adapted to engage rails to support the bucket therefrom, the bucket parts closing together by gravity when supported from said members and a bail connected to the bucket parts at points distant from the hinge whereby when the bucket is supported from said bail the bucket parts tend to open by gravity.
- 25 9. A conveyor bucket comprising two parts hinged together, laterally extending rollers adjacent the hinge adapted to engage rails to support the bucket therefrom, the bucket parts closing together by gravity when supported from said rollers and a bail connected to the bucket parts at points distant from the hinge whereby when the bucket is supported from said bail the bucket parts tend to open by gravity.
